(57) CLAIM

The ornamental design for a heel for footwear as shown and described.

DESCRIPTION

FIG. 1 is a front perspective view of a heel for footwear showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a back perspective view thereof.

The dash-dash broken lines on the heel for footwear depict portions of the heel for footwear that form no part of the claimed design. The dash-dot broken line depiction of a shoe depict environmental subject matter which forms no part of the claimed design. The dash-dot broken line at the top of the heel for footwear depicts the claim boundary.

1 Claim, 8 Drawing Sheets
